(57) **CLAIM**

The ornamental design for a running chest light, as shown and described.

DESCRIPTION

FIG. 1 is a front elevation view of a running chest light showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is a back perspective view thereof;

FIG. 9 is an enlarged view of the encircled portion in FIG. 7 that is labeled with the number “9”;

FIG. 10 is an enlarged view of the encircled portion in FIG. 7 that is labeled with the number “10”; and,

FIG. 11 is an enlarged view of the encircled portion in FIG. 8 that is labeled with the number “11”.

The dashed broken lines show portions of the running chest light that form no part of the claimed design. The dot-dash broken lines represent the boundary of the enlarged portions and form no part of the claimed design.
